UNITED STATES PATENT OFFICE.

CHARLES TOOPE, OF LONDON, COUNTY OF MIDDLESEX, ENGLAND.

GAS OR OIL BURNING STOVE.

SPECIFICATION forming part of Letters Patent No. 340,388, dated April 20, 1886.

Application filed August 27, 1885. Serial No. 175,465. (No model.) Patented in England March 6, 1885, No. 2,983.

To all whom it may concern:

Be it known that I, CHARLES TOOPE, a citizen of the United States, residing at London, England, have invented new and useful Improvements in Gas or Oil Burning Stoves, of which the following is a specification.

My invention relates to stoves adapted for burning oil or gas, and suitable for heating conservatories and halls and other similar purposes; and it has for its object to utilize the heat as effectually as possible and prevent the emission of any odor.

The stove consists of a chamber traversed by tubes, for the circulation of air and the products of combustion, and may be arranged in any of the ways hereinafter described, and illustrated in the accompanying drawings, in which—

Figure 1 is a front elevation of one arrangement of stove, partly in section. Fig. 2 is a horizontal section of same on line *xx*, Fig. 1. Fig. 3 is a vertical section; and Fig. 4, a section in the plane *zz*, Fig. 3, of the stove, the lamp and the sliding lower part of the stove being drawn out. Fig. 5 shows a modified arrangement of the heating-tubes. Fig. 6 is a horizontal section of the same on line *yy*, Fig. 5.

Similar letters indicate corresponding parts.

The stove is in all its arrangements constructed of a sheet-metal cylindrical or other shaped casing, *a*, closed at the top and fixed air-tight on a suitable base. At the lower part of the casing is a lamp-chamber separated from the upper part or main body of the stove by a horizontal partition, *d*, provided with a central aperture and a descending tube, *e*, of a size to closely inclose the lamp-glass, and constructed in two parts, the back part, *e*, being fixed to the horizontal partition, and the front part, *e'*, being hinged thereto and forming a door for the admission of the lamp-chimney into the casing thus formed, access being had to the lamp-chamber by an opening closed by the front *f'* of a sliding tray, *f*. Apertures *b* are also formed in the partition *d* at either side close to the casing *a*, and from these apertures descend legs *b'*, formed of bent pieces of sheet metal fixed against the sides of the casing *a*, said legs terminating just above the base of the stove. These legs descend into troughs formed by walls *b''* and by the sides of the casing *a*, in which the water of

condensation that escapes at the bottom of the legs *b'* is received, from which troughs it can be easily sponged out or removed. These troughs can be formed by attaching suitable pieces or strips of sheet metal of a suitable height, as shown at *b''*, Figs. 1, 2, and 5, in such a manner that the pieces of sheet metal abut at each end against the casing *a*. A trough or space is thus formed between each strip or piece of sheet metal *b''* and the casing *a*, which can be made water-tight by soldering or properly fastening the strips *b''* to the casing *a*, as well as to the bottom of the stove. The space between the strips *b''* can receive the lamp *c* and tray *f*, as shown in Figs. 2, 3, and 4. The lamp *c* rests on the tray *f*, and both are fitted to slide independently of each other between the walls *b''* of the troughs, so that (the lamp and tray being drawn out, as shown in Figs. 3 and 4) the lamp can first be pushed into position in the tube *e*, the door *e'* closed, and the tray *f* can then be slid in until its front *f'* closes the entrance to the lamp-space, as shown in Figs. 1 and 2.

Flues *g* dip into the legs *b'*, as shown in dotted lines in Figs. 1, 3, and 5, and lead out of the casing *a* into a suitable chimney or outlet, *i*.

h are air heating or circulation tubes in any suitable number and of curved or circuitous form, so as to approach for a considerable portion of their length the ascending hot current from the lamp flame, the inlet *h'* and outlet *h''* of each tube being on the side of the casing *a*. By this arrangement of the flues dipping into the apertures *b* and into the legs *b'* a better utilization of the heat, which would otherwise escape direct to the chimney, is insured, the heated current ascending at the center of the stove, as shown by arrow 1, Fig. 5, and after communicating a portion of its heat to the air-circulating tubes, and then further parting with its heat by contact with the casing *a*, descending into the legs *b'* and into the apertures *b*, whence it is drawn off by the flues *g*, as shown by the arrows 2, 2, Fig. 5, the greater part of its heat having thus been utilized.

In Figs. 5 and 6 the air-circulating tubes *h* are in the form of coils crossing each other, whereby additional heating-surface is obtained.

As seen in Figs. 3 and 5, the mouths *h'* *h''* of

the tubes h pass into openings in the casing a . When the air in the tubes h has its temperature raised, it passes out at the mouths h' into the room or space in which the stove or heater is placed, and said air thus flowing out is replaced by air from said room or space in which the stove or heater is placed, which air enters through the mouths h' into the pipes or tubes h . The air in the conservatory, room, or space in which the heater is placed thus circulates through the tubes h and becomes heated.

My heater can be provided with any suitable supply of heat—as, for example, with a gas-burner which can be made to enter the central aperture in the manner, for example, in which gas burners are made to enter apertures in the lower partition of a gas-stove in the United States Patent No. 14,325, for gas-stoves, granted February 26, 1856.

Having now particularly described and ascertained the nature of my invention and in what manner the same is to be performed, I would observe that I do not limit myself to

the particular number and arrangement of 25 the air-circulating tubes herein described, and represented in the drawings, as such may be variously modified; but

What I claim as new, and desire to secure by Letters Patent, is— 30

A stove or heater consisting of a casing and having a lamp or heating chamber at the lower part separated from the main body by a partition furnished with an inclosure for the lamp or supply of heat, an aperture to allow 35 the ascent of the hot-current tubes or tubular legs beneath said partition, communicating with openings in said partition, flues dipping into said tubes or tubular legs, and air-circulating tubes traversing the stove, substantially 40 as set forth.

In testimony whereof I have hereunto set my hand and seal in the presence of two subscribing witnesses.
